DOOR AND DOOR-FRAME FOR OVENS,
RETORTS, AND THE LIKE

Arthur Henry Lymn, London, England

Application October 3, 1935, Serial No. 43,395
In Great Britain October 4, 1934

14 Claims. (Cl. 202—248)

This invention relates to doors and door frames for ovens, retorts and other apparatus for the carbonization, distillation, or like heat treatment of coal and other carbonaceous materials.

More particularly, the invention relates to the doors and door frames of horizontal coke ovens and for the sake of simplicity the invention will hereinafter be described in its application to coke ovens although it should be well understood that it is not in any way limited to such application.

In horizontal coke ovens, it has been proposed to use a closure consisting of a rigid metal door frame coating with a metal door provided with two flexible seals. Such closures however are subject to certain drawbacks. Thus for instance, the inside of the inner seal is subjected to the action of the tar-laden distillation products and tar is deposited on the sealing surfaces of the frame and door with the result that on the withdrawal of the door and its subsequent replacement, this tar deposit tends to prevent the inner seal making a substantially gas tight joint. Moreover, as is known, the maximum gas pressure is exerted at the bottom of the door and the pressure decreases towards the top of the door. As it is difficult, if not impossible, in practice to keep the inner seal gas tight, the gas leakage which takes place past this seal exerts pressure on and has to be stopped by the outer seal with a consequent fouling of the sealing surfaces of the latter, thus entailing the labour of cleaning the said surfaces.

The present invention aims at obviating the foregoing disadvantages.

Accordingly, one object of the invention is to provide a door having two or more flexible seals the inner of which is so arranged as to scrape and clean the inner sealing surface of the door frame.

A further object of the invention is to provide an outer metal-to-metal seal between the door and the door-frame which comprises a flexible plate secured to and surrounding the door body and carrying a packing frame of known type, arranged at right angles to a seating surface on the door-frame and applied to said seating surface by a series of set screws.

A further object of the invention is to provide inner and outer seals each consisting of a dished flexible and adjustable metal plate arranged to bear against an inclined surface or surfaces on the door-frame.

A further object of the invention is to provide an inner seal or seals consisting of a dished,

flexible and adjustable metal plate or plates arranged to bear against an inclined surface or surfaces on the door-frame, whilst the outer seal consists of an asbestos or like packing mounted at the end of an adjustable flexible plate and arranged to bear against the door-frame face.

Still a further object of the invention is to provide a closure of the foregoing general type having tightening means operable in common by a single operating mechanism, in a simple and efficient manner.

Further objects and advantages of the invention will become apparent as the description thereof proceeds.

In order more clearly to understand the invention, reference is made to the accompanying drawings which illustrate by way of example, several embodiments thereof and in which:—

Fig. 1 is a partial front elevation of one embodiment;

Fig. 2 is a plan section through the line A—A of Fig. 1;

Fig. 3 is a view on a larger scale of a detail of Fig. 2;

Fig. 4 is a transverse section through the middle of Fig. 1;

Fig. 5 is a plan section of a second embodiment;

Fig. 6 is a detail showing an alternative sealing arrangement;

Fig. 7 is a plan section of still another embodiment; whilst

Fig. 8 is a detail on a larger scale of part of the coke-oven door of Fig. 7.

In all the figures like parts are denoted by like characters of reference.

In the embodiment illustrated in Figs. 1 to 4, 1 denotes the door-frame which is held in position in the oven brickwork by means of buckstays 2.

The door, fitting into the door-frame 1, is built up of sections and comprises two vertical steel joists 4, 4 suitably braced. Said joists 4 may obviously be replaced by girders of U or channel section or by castings if desired.

The outer or main seal of the door is constituted by a flexible mild steel plate 5 secured to the webs of the joists 4 and adapted to bear on the part 1a of the door-frame 1.

Bolted or otherwise secured to each plate 5 is an angle bar 5a which bears against the seating surface 1a.

Alternatively the plate may be flanged all round with the edge of the flange bearing against the seating surface 1a.

An inner seal is formed by laminated flexible steel plates 6 mounted between the rear flanges 4b of the joists and a plate 10 forming part of the door. The flexible steel plates 6 are so disposed that on closing the door the inner plates of each assemblage scrape and clean the sealing surface 1b of the door-frame whilst the outer plate or plates, which do not come into contact with the tar-laden vapours and are consequently substantially clean, make a substantially gas-tight joint with the cleaned sealing surface 1b. Moreover the laminated plates 6 assembled together in the manner more clearly shown in Fig. 3 are able to adjust themselves individually to any inequalities in the sealing surface 1b and thus enhance the gas tightness of the inner seal.

The outer surface of the outermost, and if desired the outer surface of one or more of the remaining flexible plates 6 of each assemblage may be covered with heat-insulating material whereby condensation and deposition of tarry matters on the plates 6 can be reduced to a minimum.

Bolted on the plate 10 are lugs 11 which are each provided with set screws 12 adapted to adjust the pressures with which the periphery of the flexible members 6 bears against the oblique rear edges 1b of the door-frame.

Secured to the front flanges 4a of the joists are a series of bridge members 14 which are provided at their ends with bosses through which pass set screws 13 adapted to bear on the periphery of the flexible plate 5 to adjust the pressures with which it bears against the surfaces 1a of the door-frame 1 so as to allow for any inequalities caused by warping of the door-frame.

Between joists 4 are angle plates 21 securing blocks 20 which house a screw 22 on which is mounted a locking bar 23 adapted to engage behind plates 24 mounted on the buckstays 2 to thrust on the whole door when it is locked. The individual screws 22 are provided with a squared end 28 so as to enable them to be operated by a spanner to adjust the thrust of the locking bars. The various locking bars 23 (two in general, of which only one is shown in Figs. 1 to 3) are inter-connected by means of an operating rod 25 so that all locking bars 23 are operated together. On an upward pull of the rod 25, the locking bar 23 enters into the position shown in dotted lines in Fig. 1 and is thus no longer held by the plates 24, thereby allowing the door to be opened.

The door jambs or flash plates right round the door opening 1 are tapered inwards at their rear end and the flexible sealing member 5 is continued all round the door so that the seal is complete. Similarly the flexible laminated plates 6 are dished all round the door.

Secured to the plate 10 and rear flanges 4b of the joists by brackets 7 are cast iron boxes or holders 8 containing a refractory lining 9 exposed to the heat of the oven. This arrangement ensures a flexible structure which cannot crack if warping should take place and which can easily be straightened.

Moreover, the provision of the brackets 7 causes a space 26 to be formed between the box 8 and the plate 10 through which the gas generated at the bottom of the ovens can pass freely from the bottom of the ovens to the top of the coal charge inside the inner seal 6 in the door itself.

In the embodiment illustrated in Fig. 5, the inner seal is formed by the flexible steel plate 6 which is mounted at the rear of the plate 10 forming

ing a part of the door and the periphery of which bears against the inclined surfaces 1b of the frame 1. The outer seal is likewise formed of a flexible flanged steel plate 40 which is bolted to the webs of the channels 4 of the door, the periphery thereof likewise bearing against the inclined surfaces 1b. Lugs 41 adjustable in a horizontal direction are carried on screwed spindles 42 by means of which the flexible steel plates forming the outer seal are adjusted to allow for any inequalities caused by warping of the door frame 1.

The coke oven door is provided, as in the case of the previous embodiment, with a series of locking bars 23 interconnected by an operating rod, 15 one of said locking bars being shown and which is adapted to engage behind retaining members 43, so as to thrust on the door when it is locked.

Secured to the plate 10 and the main door channel member by brackets are cast iron boxes 20 or holders 8 containing a refractory lining 9, which is exposed to the heat of the oven in the manner described in the foregoing embodiment the spacing between the box 8 and plate 10 enabling the gas generated at the bottom of the oven to pass freely to the top of the coal charge in the door itself inside the inner seal 6.

In the embodiment shown in Fig. 6, the inner seal 6 is similar to that described with reference to the foregoing embodiment in that the outer periphery of the seal bears against the inclined surfaces of the door frame 1b. The seal 6 is however, secured to the webs of the channels by means of bolts 44 in slotted holes which allow for some adjustment of the inner seal 6 in a 35 horizontal direction.

The outer seal consists of a flexible plate 5 flanged at its inner side and attached to the webs of the channel members of the door. At the outer edge of the flexible plate 5, asbestos packing 45 is carried in a slot formed by a metal strip 46 and angle 47 attached to the flexible plate.

Adjustment of the outer seal is carried out by means of set screws 48 in the brackets 49 which are likewise attached to the channel member of 45 the door, the set screws 48 being adapted to bear on and press the extremity of the flexible plate 5, thus forcing the projecting asbestos packing 45 against the face of the door frame.

In order to allow for wear of said asbestos 50 packing 5b, the set screws 48 are turned down at the ends 50 which pass through holes in the flexible plate 5 to bear on a metal strip 51 placed in the box behind the asbestos packing. Thin washers 52 are placed on the ends of the set 55 screws 48 between their shoulders and the flexible plate 5 and when the asbestos packing 45 needs adjustment one or more of these washers is removed, thus allowing the reduced ends of the set screws to bear on the metal strip 51 and 60 thus force the asbestos packing 45 forward.

In the embodiment of coke oven door illustrated in Figs. 7 and 8, the inner seal 6 is substantially similar to the seal 6 of Fig. 6, but the outer seal 5 is adapted to be adjusted either by pressing it 65 against the door frame 1, or by pulling it in an outward direction.

Moreover, the outer seal itself is constituted by a packing 52 of asbestos which is bolted on to an angle 53 and thus secured at right angles 70 to the flexible plate 5 and can be brought to bear against the edge of the door frame 1. The flexible plate 5 is flanged at its inner side and bolted to the channel members 4 of the door. Adjusting of the seal is effected by means of threaded 75

eye bolts 54 passing through right-angled brackets 55 also attached to the channel 4, the eyes 54 means for coupling said locking bars together, 56 fitting into lugs or cups 57 which latter are means for adjusting the bearing pressure of each 5 attached to the flexible plate 5. It will thus be seen that said plate 5 can be pushed towards or pulled away from door frame 1 by screwing up or unscrewing the eye bolts 54.

The asbestos packing 52 is arranged to project beyond the flange of the angle 53 to which it is attached, since the asbestos conforms more closely and more easily than metal to any irregularities in the co-acting metal sealing surface and can be adjusted in known manner, for example by providing slotted holes in the angle 53, in order to compensate for the deterioration or wear of said asbestos which may occur.

The foregoing constructions are equally advantageous in cases where the seals are made on an auxiliary renewable door-frame thoroughly insulated from, and mechanically attached to the main door-frame so that it does not partake of the distortion of the latter.

In the embodiment illustrated in Fig. 6, the door frame 1 is represented as being of the type which is adapted to be renewed, and is thoroughly insulated from, and mechanically attached to the main door frame so that it does not partake of the distortion of the latter.

It should be well understood that the embodiments hereinbefore described are given purely by way of example and are not intended in any way to limit the scope of the invention which is intended to be covered in its broadest aspects by the appended claims.

35 I claim:—

1. A closure for apparatus, such as coke ovens and retorts, operating at elevated temperatures, said closure comprising a rigid metal door-frame and a metal door, a metal plate secured to said door and bearing on a part of the door-frame to form an outer seal and a plurality of flexible metal plates secured together at one edge and gearing with their other ends on an inner part of said door-frame to form an inner seal.

45 2. A closure for apparatus, such as coke ovens and retorts, operating at elevated temperatures, said closure comprising a rigid metal door-frame and a metal door, a metal plate secured to said door and bearing on a part of the door-frame to form an outer seal, and an inner seal consisting of a plurality of flexible metal plates secured together at one edge and bearing with their other ends on an inner part of said door-frame so as to adjust themselves individually to any inequalities in said door frame.

55 3. In a coke oven, a stationary door-frame, a door body, abutting sealing surfaces on said door-frame and said door body, an outer elastic sealing plate arranged on said door body adapted to engage with a sealing surface on said door-frame, a plurality of inner elastic sealing plates arranged on said door body behind said outer sealing plate and adapted to engage with an inner sealing surface of the door frame, and a covering 65 of heat insulating material on the outer surface of at least one of said inner elastic sealing plates.

4. A closure for apparatus, such as coke ovens and retorts, operating at elevated temperatures, said closure comprising a rigid metal door-frame 70 and a metal door, a metal plate secured to said door and bearing on a part of the door-frame to form an outer seal, a plurality of flexible metal plates secured together at one edge and bearing with their other ends on an inner part of said door-frame to form an inner seal rotatable lock-

ing bars mounted on the main door structure, and means for coupling said locking bars together, means for adjusting the bearing pressure of each attached to the flexible plate 5. It will thus be seen that said plate 5 can be pushed towards or pulled away from door frame 1 by screwing up or unscrewing the eye bolts 54.

5. A closure for apparatus, such as coke ovens and retorts, operating at elevated temperatures, said closure comprising a rigid metal door-frame and a metal door, a metal plate secured to said door and bearing on a part of the door-frame to form an outer seal, a plurality of flexible metal plates secured together at one edge and bearing with their other ends on an inner part of said door-frame to form an inner seal, rotatable locking bars mounted on the main door structure, a screw spindle passing through each locking bar and screwed into the door structure, tightening nut on each screw spindle, and means operatively interconnecting the screw spindles on the several locking bars.

20 6. A closure for apparatus such as coke ovens or retorts operating at elevated temperatures, said closure comprising a rigid metal door frame and a metal door having an outer dished flexible and adjustable metal plate bearing on an inclined 25 surface on the door frame and an inner dished flexible plate bearing on another inclined portion of the door frame.

7. A closure for apparatus such as coke ovens or retorts operating at elevated temperatures, 30 said closure comprising a rigid metal door frame and a metal door having an outer dished flexible plate adjustable by lugs loosely mounted on threaded spindles and bearing on an inclined surface on the door frame and an inner dished 35 flexible plate bearing on another inclined portion of the door frame.

8. A closure for apparatus such as coke ovens or retorts operating at elevated temperatures, said closure comprising a rigid metal door frame 40 and a metal door having an outer dished flexible plate adjustable by lugs loosely mounted on threaded spindles and bearing on an inclined surface on the door frame and an inner dished 45 flexible plate bearing on another inclined portion of the door frame and adjustable by means of bolts in slotted holes in the door structure.

9. A closure for apparatus such as coke ovens or retorts operating at elevated temperatures, said closure comprising a rigid metal door frame 50 and a metal door having an outer seal with a packing of fibrous material mounted round the outside edge of an adjustable flexible plate and arranged to bear against the door-frame face and an inner seal consisting of dished flexible and 55 adjustable metal plates fixed to the door and arranged to bear against an inclined surface or surfaces on the door frame.

10. A closure for apparatus such as coke ovens or retorts operated at elevated temperatures, 60 said closure comprising a rigid metal door frame and a metal door having an outer seal with a packing of asbestos mounted round the outside edge of an adjustable flexible plate and arranged to bear against the door-frame face and an inner 65 seal consisting of dished flexible and adjustable metal plates fixed to the door and arranged to bear against an inclined surface or surfaces on the door frame.

11. A closure for apparatus such as coke ovens 70 or retorts operating at elevated temperatures, said closure comprising a rigid metal door frame and a metal door having an outer seal with a packing of fibrous material mounted round the outside edge of a flexible plate and arranged to 75

bear against the door-frame face with a pressure which is adjustable by means of set screws and an inner seal consisting of dished flexible and adjustable metal plates fixed to the door and arranged to bear against an inclined surface or surfaces on the door frame.

12. A closure for apparatus such as coke ovens or retorts operating at elevated temperatures, said closure comprising a rigid metal door frame and a metal door having an outer seal with a packing of fibrous material mounted round the outside edge of a flexible plate which is arranged to bear against the door-frame face the pressure being controlled by eye-bolts co-acting with the outer seal and arranged to exert pull as well as pressure, and an inner seal consisting of dished flexible and adjustable metal plates fixed to the door and arranged to bear against an inclined surface or surfaces on the door frame.
13. A closure for apparatus such as coke ovens or retorts operating at elevated temperatures, said closure comprising a rigid metal door frame and a metal door having an outer seal with a

packing of asbestos mounted between metal strips round the outside edge of an adjustable flexible plate and adjustable relative to said strips, said packing being arranged to bear against the door-frame face and an inner seal consisting of dished flexible and adjustable metal plates fixed to the door and arranged to bear against an inclined surface or surfaces on the door frame. 5

14. A closure for apparatus such as coke ovens or retorts operating at elevated temperatures, 10 said closure comprising a rigid metal door frame and a metal door having an outer seal with a packing of asbestos mounted between metal strips round the outside edge of an adjustable flexible plate and adjustable relative to said strips by 15 means of set screws arranged in the rear of said asbestos, said packing being arranged to bear against the door-frame face and an inner seal consisting of dished flexible and adjustable metal plates fixed to the door and arranged to bear 20 against an inclined surface or surfaces on the door frame.

ARTHUR HENRY LYMN.

CERTIFICATE OF CORRECTION.

Patent No. 2,038,051.

April 21, 1936.

ARTHUR HENRY LYNN.

It is hereby certified that error appears in the printed specification of the above numbered patent requiring correction as follows: Page 3, first column, line 43, claim 1, for the word "gearing" read bearing; and second column, line 60, claim 10, for "operated" read operating; and that the said Letters Patent should be read with these corrections therein that the same may conform to the record of the case in the Patent Office.
